UNITED STATES PATENT OFFICE.

ALFRED JOHN BROWN AND GEORGE I. PAULSON, OF BROOKLYN, NEW YORK.

NONRESALABLE BOX.

Application filed July 8, 1919, Serial No. 309,463. Renewed March 8, 1922. Serial No. 542,162.

To all whom it may concern:

Be it known that ALFRED J. BROWN and GEORGE I. PAULSON, citizens of the United States, residing at Brooklyn, in the county 5 of Kings and State of New York, have invented new and useful Improvements in Nonresalable Boxes, of which the following is a specification.

This invention relates to containers and 10 more particularly to boxes for the reception of confections such as candy and the like, but is not necessarily limited to this use.

One of the primary objects of the invention is the provision of an article of the 15 class described provided with means for securing the body and cover members together in order to prevent opening of the box without mutilation of the same.

Another object of the invention is the provision of an article of the class described 20 which is so constructed as to readily allow the same to be associated with any standard container construction of this class.

Another object of the invention is the provision of a device which is of simple construction, inexpensive to manufacture and 25 which provides means for positively preventing the removal of the contents from the box without mutilation of the same.

With these and other objects in view the invention resides in the novel construction, combination and arrangement of parts fully described in the following description and 30 claims and illustrated in the accompanying drawings in which:

Figure 1 is a perspective view of a box with the device associated therewith.

Figure 2 is a detail sectional view of the same.

Figure 3 is a perspective view of one of the details of the invention.

Referring to the drawings we have shown a standard box construction which consists of a body member 10 which is provided with 45 the usual bottom 11, sides 12 and ends 13 and secured to said bottom 11 is the supplementary bottom 14. The cover member 15 comprises the top 16, sides 17 and ends 18 and is provided with a supplementary top 19 over 50 which is arranged the covering 20 which contains thereon the usual advertising matter. The means for mutilating the cover consists of a pair of flexible elements 21 and 22 which are here shown as constructed 55 of fine wire, the central portions of which

are intertwined as at 23 and are provided at their extremities with the loops 24 which are engaged over corners of the supplementary top 19 and normally hidden by the covering 20. The locking device includes a tubular threaded member 25 which is provided with a flange 26 having a plurality of spurs 27 upturned from its periphery. The member 25 is inserted in a centrally arranged opening 28 provided in the bottom 11 of the body portion and is covered by the supplementary bottom 14. A tubular threaded member 29 is provided for engagement with the threaded portion 30 of the member 31, said member being provided with a threaded portion 32 at its opposite extremity which engages with the member 25. The member 29 is provided with the resilient tongues 33 which project inwardly and downwardly from the interior of the same for a purpose 75 to be hereinafter set forth. After the member 25 has been secured to the bottom of the box and supplementary bottom 14 arranged in place the member 31 is threaded 80 engaged with the same and the member 29 engaged with the member 31. The contents of the box are then placed therein and the cover member arranged thereon. A centrally arranged opening is provided through the top 16, supplementary top 19 and covering 20 and a key 34 provided with a shank 35 is inserted through the opening and arranged within the tubular member 29. Depressions 36 are provided in the key which are adapted to be engaged by the tongues 33, 85 whereby the key is secured against removal from the member 29. The shank 35 is slotted as at 37 and receives the twisted portion 23 of the flexible elements 21 and 22.

It will thus be seen that in order to remove the cover from the body member it is necessary to turn the key 34 in order to separate the member 29 from the member 31 and and by so doing the twisted portion 23 is wound upon the shank 35 of the key. This 100 operation will cause the flexing of the supplementary top 19 thus mutilating the same to such an extent as to inform a subsequent purchaser that the box has been tampered with and inferior goods substituted for the 105 genuine.

While we have illustrated and described a simple and preferred form of carrying our invention into practice, we do not care to be limited to the exact details therein 110

exhibited but reserve the right to make such changes and alterations as fall within the scope of the appended claims.

What is claimed as new is:

- 5 1. A container including a body member, a cover for the body member, a device including interlocking parts and a manipulator, and means connected to the manipulator for mutilating the cover upon the manipulation of the manipulator. 40
- 10 2. A container including a body member and a cover therefor, a locking device for securing the body member and the cover together, a manipulating member adapted to form a part of the device in the securement of the body member with the cover and constituting means for unlocking the same, and means conjoined with said cover and connected to said manipulating member for 45 mutilating said cover upon the manipulation of said manipulating member. 50
- 15 3. A container including a body member and a cover therefor, locking members secured to the body member and the cover respectively and provided with means for holding said locking members against separation, a manipulator adapted to form a part of one of said locking members and constituting a device for separating the said 55 members, and means conjoined with the cover and connected to the manipulator for mutilating the cover upon manipulation of the manipulator in the separation of said locking members. 60
- 20 4. A container including a body member 65
- 25
- 30
- 35

and a cover therefor, means for mutilating the cover, normally connected separable means for securing the body member and cover together, a manipulator adapted to be conjoined with said means for the securement of the body member and the cover together and constituting a device for separating the said members, the first mentioned means being connected to the manipulator for the operation thereof. 45

5. The combination with a container having a body member and a cover member, of means for mutilating the cover member, a separable element secured to the body member, a device adapted to engage with said element for securing the cover to the body, said device co-acting with the mutilating means whereby to destroy the cover upon manipulation of the device to unlock said cover from the member. 55

6. The combination with a container having a body member and a cover member, of means for mutilating the cover member, a separable element secured to and arranged within the body member, a device adapted to engage with said element for securing the cover to the body, said device co-acting with the mutilating means whereby to destroy the cover upon manipulation of the device to unlock said cover from the member. 65

In testimony whereof we have affixed our signatures.

ALFRED JOHN BROWN.
GEORGE I. PAULSON.
